UNITED STATES PATENT OFFICE.

JOHN KNOCHE, OF CLANCEY, MONTANA TERRITORY.

AMALGAMATOR.

SPECIFICATION forming part of Letters Patent No. 309,148, dated December 9, 1884.

Application filed October 16, 1883. (No model.)

To all whom it may concern:

Be it known that I, JOHN KNOCHE, a citizen of the United States, residing at Clancey, in the county of Jefferson and Territory of 5 Montana, have invented certain new and useful Improvements in Devices for Washing, Separating, Concentrating, and Amalgamating Ores, of which the following is a specification.

This invention relates to a device for the 10 separation, concentration, and amalgamation of ores. Its object is to save the lighter particles of the precious metals which in the ordinary washers and concentrators are carried off during the process.

15 With this object in view the invention consists in the peculiar shape of the budle and the shape and arrangement of the shoes by which the pulp undergoing treatment is prevented from splashing over the budle and 20 carried toward the center.

It also consists in certain details of construction and combination of parts, all of which will be first fully described, and then particularly pointed out in the claims.

25 In the accompanying drawings, in which similar reference-letters indicate like parts wherever they occur in the different views, Figure 1 is a view, partly in central vertical section and partly in side elevation, of my 30 proved device. Fig. 2 is a top plan view on a reduced scale of the bottom of the pan or budle. Fig. 3 is a vertical transverse section taken through the rotating arm, showing one of the mixing-shoes and muller in end elevation. Fig. 4 is a transverse section taken 35 through line $\alpha\alpha$ of Fig. 3.

The bar from which the shoes are suspended is shown in dotted line to represent the relative positions of the bar and shoes when 40 set in place. The shoes are shown in top plan view. The pan or mixing-vessel A has its rim inclined inward toward the top, the shape of the vessel being the frustum of a cone. It is preferably made of wood. The 45 bottom is lined or paved with stone or cast-iron. This lining B, Fig. 2, is grooved from the periphery to the center. The grooves b are curved or angular, so as to allow the shoes C to slide around the bottom without catch- 50 ing on the edges of the grooves when the shoes

are used as mullers to grind the pulp upon the bottom B. The grooves b gradually deepen from the rim toward the central discharge-opening, b' . The vessel is secured in a frame, D, in which is mounted a vertically-sliding 55 revolving shaft, E. On the lower end of the shaft E is secured to be revolved by the shaft an arm, F. This arm is perforated with two rows of holes—one row upon each side of its central line—to receive the shafts or bars c, to 60 which the shoes C are suspended. The bars c are secured in the rotating arms F by nuts above and below the arms F, so that the shoes are vertically adjustable in the arms to compensate for the unequal wear of the shoes. 65 The arms F are by similar means vertically adjustable on the shaft E. The shoes C are circular on their leading faces, and taper from their outer top edges down toward their inner top edges. They are placed diagonal to the 70 arm F, so that the outer ends of the shoes lead when the arm F revolves.

The object of the particular shape and arrangement of the shoes is to overcome the centrifugal force imparted to the contents of the 75 vessel by the mixers C and carry the contents toward the center. The shoes upon the opposite sides of the central shaft are so placed that they traverse different circular paths, those upon one side following between the paths traversed by those upon the opposite side; thus the whole of the pulp is brought under their action, and when used as grinders upon the bottom of the pan every part of the bottom is rubbed by the shoes. I have shown but two 80 arms, F, extending from the center upon opposite sides of the driving-shaft E; but the number may be increased to suit the work being done, and the size and number of the shoes used may of course be varied without 85 departing from the principle of the invention. The vertically-sliding shaft E, with its connections, is elevated and lowered by means of the lever G, which has its fulcrum in a post, d, projecting up from the top rail of the frame 90 D. The forked end of the lever embraces the shaft between a fixed collar, e, and the driving-pulley H. Below the driving-pulley is another collar, e'. The two collars are secured upon the shaft by set-screws, and the driving- 95 100

pulley is splined upon the shaft, so that the shoe-frame or arm F may be set to any position relative to the bottom of the pan A. The lever G is operated by a cord, g, attached to a brake-lever, windlass, or other suitable mechanism to elevate the shaft E and the mixing-shoes.

Back of the shoes C are plates c', of copper. These are held against the shoes by the bars c, between which and the shoes the copper plates are clamped by the screws which secure the shoes in place. To these plates some of the mercury used in the process of amalgamating adheres, and the very divided metal is collected upon the plates.

The operation of the device is as follows: The crushed or ground ore, as it comes from the mill is placed in the vessel A to the proper depth, the shoes being at the time elevated above the vessel. A stream of water is turned into the pan and the shoes let down to their work. They first act upon the top of the ore, and are gradually let down as the pulp becomes thoroughly mixed. The quicksilver which has been placed in the pan gradually settles into the grooves b, and during the operation all parts of the pulp are brought successively in contact with the mercury. During the rotation of the shoes around the pan there is no tendency of the water or the pulp to be splashed over the top of the vessel, while the earthy light substances will be carried off with the overflow. When the overflow is clear, the light earthy matter will have been all washed out of the pulp, leaving the rich ore and sulphates. The shoes are now elevated to clear the upper edge of the vessel, and the water decanted or drawn off, after which the mercury or amalgam is drawn off through the center opening. Through an opening in the vessel A, on a level or a little below the level of the floor B, the mineral substances are then removed and the vessel is ready to receive another charge.

The copper plates c', when charged with amalgam, may be removed and cleaned.

It is evident that the cone-shaped vessel A may be used to advantage with the ordinary mullers now in use, and that my particular arrangement of shoes or mullers may be used to advantage with the common amalgamating or concentrating pans.

I am aware that it has been heretofore proposed to so arrange the driving mechanism

of an amalgamating machine as to admit of the raising and lowering the mullers without interfering with their rotation, in order that said mullers may be operated at a greater or less distance from the bottom of the pan; but I am not aware that any one prior to my invention has ever proposed so constructing such a machine that the mullers may be raised entirely clear of the upper edge of the pan without disconnecting the muller-shaft from the source of power.

I am aware that it is not broadly new to secure copper strips or plates to the mullers or shoes of amalgamators; but I am not aware that such copper plates have heretofore been secured to the backs of said shoes by the same means which secures the shoes to their holders or supports, thereby providing for the ready adjustment or removal of said plates.

What I claim as new, and desire to secure by Letters Patent, is—

1. The combination, substantially as before set forth, of the amalgamating-pan, the side walls of which slope inwardly toward the top, and the rotary mullers having their leading faces arranged diagonal to the radii of the pan, whereby the pulp is deflected toward the center of the pan by the rotary movement of the mullers.

2. The combination, with the amalgamating and the rotating arm, of the mullers tapering from their outer to their inner ends, and having their concaved leading faces arranged diagonally with relation to the radii of the pan, whereby the pulp is directed toward the center of the pan by the rotary movement of the mullers, substantially as described.

3. The combination, with the mixing-vessel and the frame, of the rotating shaft, the collars e e', for adjustably securing said shaft, and the bifurcated lever for raising the mullers to clear the upper edge of the vessel and lowering them to their work while the machine is in operation, substantially as described.

4. The combination, with a shoe or muller of an amalgamating device, of a copper plate, c', detachably secured to the back of the shoe for the purpose of collecting the lighter particles of the precious ores.

JOHN KNOCHE.
